CLAIM

The ornamental design for a lawn mower as shown and described.

DESCRIPTION

The patent or application file contains at least one drawing executed in color. Copies of this patent or patent application publication with color drawing(s) will be provided by the Office upon request and payment of the necessary fee.

1. Lawn mower

1.1: Front right and top perspective view

1.2: Back left and bottom perspective view

1.3: Front

1.4: Back

1.5: Left

1.6: Right

1.7: Top

1.8: Bottom

1.9: Enlarged

4.1: Front right and top perspective view

4.2: Back left and top perspective view

4.3: Back left and bottom perspective view

4.4: Front

4.5: Back

4.6: Left

4.7: Right

4.8: Top

4.9: Bottom

The even-dash broken lines in the drawings illustrate portions of the lawn mower that form no part of the claimed design. The dot-dash broken lines in 1.1 and 1.9 are imaginary lines that are included for reference purposes only to identify the enlarged views; The dot-dash broken lines in 1.1 and 1.9 form no part of the claimed design. The color shown on the claimed design forms no part thereof.
